DESIGN FOR A SHELFED BRACKET

John P. Nichols, Philadelphia, Pa.

Application February 26, 1943, Serial No. 109,629

Term of patent 14 years

To all whom it may concern:

Be it known that I, John P. Nichols, a citizen of the United States of America, residing at Philadelphia, in the county of Philadelphia and State of Pennsylvania, have invented a new, original, and ornamental Design for a Shelved Bracket, of which the following is a specification, reference being had to the accompanying drawing, forming part thereof.

Fig. 1 is a front elevational view of the shelved bracket, showing my new design;

Fig. 2 is a right side elevational view; and
Fig. 3 is a top plan view.

I claim:

The ornamental design for a shelved bracket, substantially as shown.

JOHN P. NICHOLS.
